UNITED STATES PATENT OFFICE.

CARL P. BOHLAND AND JOSEPH J. CONNELLY, OF SUPERIOR, WISCONSIN; ANNA M. CONNELLY ADMINISTRATRIX OF JOSEPH J. CONNELLY, DECEASED.

MOLDING-MACHINE.

972,781.

Specification of Letters Patent. Patented Oct. 11, 1910.

Application filed December 10, 1909. Serial No. 532,370.

To all whom it may concern:

Be it known that we, CARL P. BOHLAND and JOSEPH J. CONNELLY, citizens of the United States, residing at Superior, in the 5 county of Douglas and State of Wisconsin, have invented certain new and useful Improvements in Molding-Machines, of which the following is a specification.

Our invention relates to an improvement 10 in molds, and more particularly to the molds for bins or tanks which are circular in shape and intended for storing grain and the like.

The object of the invention is to provide 15 means whereby the mold can be raised after the first section of the bin is formed, and the mold, after having been raised the desired distance, is secured or locked upon the molded article or section, when the mold is again filled with the cement or concrete for 20 building the bin the desired height.

The invention consists in certain novel 25 features of construction and combinations of parts which will be hereinafter described and pointed out in the claims.

In the accompanying drawings Figure 1 is a view in elevation, showing the concrete structure and walls of the mold in section; Fig. 2 is a vertical section; and Fig. 3 is a detail view, showing the manner 30 of connecting the pipes which are used as a reinforcement in the concrete structure.

A, A, represent the uprights and B, B, the walls of the mold which are connected to the uprights A. A bar 1 is rigidly connected to one of the uprights A by means of bolts 2 passing through an angle plate 3 connected to the uprights. The other end of the bar slides beneath an angle plate 4 and in a recess formed in the annular plat- 40 form C which extends around the interior of the mold. A tube or rod 5 is received between the walls of the mold B and is embedded in the concrete or cement for forming a reinforcement for the concrete wall.

The rod or tube extends through an opening 45 formed in the bar 1 upwardly between the uprights A. The U-shaped yoke 6 is received around the uprights A and the ends of the yoke are connected together and held 50 upon the uprights by plate 7 and nuts 8. A lever 9 is pivotally connected to one of the uprights A and is also connected to the yoke 6. When the lever 9 is thrown down- 55 wardly against the platform C, the up- rights A are drawn together, causing the

walls B to be drawn toward each other. But when the lever is thrown upwardly practically parallel with the uprights A, the walls will separate from each other slightly, or sufficiently to allow the mold to be drawn 60 upwardly. Pivotaly mounted upon the upper surface of the bar 1 are dogs 10, 10, which are adapted to engage the tube 5 for supporting the mold upon the molded wall. A cross beam 11 connects the uprights at 65 their upper ends and an opening 12 is formed therein through which the rod or tube 5 passes. Mounted upon the beam over the opening is a collar 13, which is provided with an annular groove 14. The 70 collar is preferably made in two sections and received between the sections is the hub 15 of a wheel 16. Upon the hub 15 is an annular rim 17, which is adapted to be received in the groove 14. A screw-threaded 75 sleeve 18 is received over the tube 5 and is adapted to pass through the opening 12 to the beam 11, and the hub 15 of the wheel 16 is screw-threaded, whereby a screw-threaded engagement is formed between the 80 sleeve 18 and the wheel 16. Connected to the lower end of the sleeve 18 is a guide-plate 19 which is provided with forked ends 20, between which are received the uprights A, the plate being held upon the sleeve by a 85 thumb-screw 21 which prevents the sleeve from turning. Arms 22 are formed on the sleeve and pivotally connected to the arms by means of links 23 are dogs 25, which dogs are provided with openings through 90 which the rod 5 extends, and the dogs are adapted to engage the rod for locking and retaining the mold in its raised position. The under surface of the plate 19 is beveled from the center toward the ends, as indi- 95 cated by the dotted lines 26.

Assuming that the cement or concrete has been poured into the mold and formed into the proper shape, and it is desired to raise the mold for building the wall higher. The 100 lever 9 is raised, whereby the walls B are released from the walls of the molded article, wheel 16 is then turned to the left, which causes the uprights A and walls B of the mold to move upwardly, sleeve 18 remaining stationary. The wheel is turned until the walls of the mold have been brought to about within 6 inches from the top of the molded wall. After this adjustment has been obtained, the lever 9 is thrown down, 110

causing the walls to be brought into engagement with the walls of the molded article. After this operation of raising the mold, there will be little of the sleeve left for the 5 raising operation. The dogs 25 have been supporting the mold during the raising operation, and before the screw sleeve is raised upwardly for the next operation, the wheel 16 will be continued to move upwardly until 10 the plate 19 has engaged the dogs 10, causing them to firmly grip the tube 5. As the dogs 10 continue to move upwardly on the bar 1, the upper ends of the dogs will engage the beveled surfaces of the plate 19, which will 15 cause them to be forced against the pipe or tube 5. After this has been accomplished, the wheel 16 will be turned to the right, causing the sleeve 18 to be raised and the dogs 25 released from engagement with the 20 tube. The sleeve will be raised to the desired height, when the mold can again be raised upon the turning of the wheel 16 to the left, after the lever 9 has been raised to its vertical position. This operation is continued until the wall is made to the proper 25 height. Of course, if occasion demands, the raising or lowering of either the sleeve or the mold may be performed at any intermediate point. In Fig. 3 we have disclosed the 30 manner of connecting the tubing together. When the top of a tube has been reached in the molding operation, and it is desired to add another length of piping, two short lengths of piping 27 are provided, which are 35 screw-threaded and connected to which is a coupling 28. An end of each of the pipes 27 is adapted to be received within the tubing 5. After the two pipes have been connected together, they will take the position 40 as indicated by the dotted lines, thereby presenting a smooth surface for the dogs 10 and 25 to grip during the operation of raising the mold.

We do not care to limit ourselves to any 45 particular formation of wall which may be constructed with our device, as it can easily be adapted to a straight wall, or any other shaped wall as well as the circular wall, and hence we do not care to be limited to the 50 exact construction set forth, but:—

Having fully described our invention, what we desire to secure by Letters Patent, is:—

1. The combination with a mold having a collar mounted thereon, of a screw-threaded

sleeve, a rod passing through the sleeve, 55 means for connecting the sleeve to the rod, and a screw-threaded nut having a screw-threaded engagement with the sleeve rotatably mounted in the collar, whereby upon the rotation of the nut the mold is caused to 60 be moved.

2. The combination with a mold, of a rod, raising means engaging the rod for causing the mold to be raised, and a clutch on the mold adapted to be operated by the raising 65 mechanism for locking the mold against movement upon the rod.

3. The combination with a mold, of a sleeve, a rod passing through the sleeve, clutching means for engaging the rod, means 70 engaging the sleeve for causing the mold to be raised, and for causing the sleeve to engage the clutching means for locking the mold against movement upon the rod whereby the sleeve may be returned to its original 75 position before the raising operation.

4. The combination with a mold, of a sleeve, a rod extending through said sleeve, clutching means adapted to engage the rod, and means adapted to engage the sleeve for 80 causing the mold to be raised and to cause the clutching means to engage the rod, whereby the mold will be locked against downward movement.

5. The combination with a mold, of screw- 85 threaded sleeve, a rod passing through the sleeve, means on the sleeve adapted to engage the rod, a guide-plate connected to the sleeve, and a rotatable nut adapted to engage the sleeve for causing the mold to be 90 moved upwardly.

6. The combination with a mold, of a screw-threaded sleeve, a rod passing through the sleeve, dogs adapted to engage the rod, a guide-plate on the sleeve, a rotatable nut engaging the screw-threaded sleeve for causing the mold to be raised and causing the plate to engage the dogs for locking the mold in its raised position, said nut adapted to return the sleeve to its normal or original position. 95

In testimony whereof we affix our signatures, in the presence of two witnesses.
